US0D1059291S

(12) **United States Design Patent** (10) **Patent No.:** **US D1,059,291 S**
(45) **Date of Patent:** **** Jan. 28, 2025**

(54) **FIBER OPTIC CONNECTOR**

(71) Applicant: **OptoMedia Technology Inc.**, Zhubei (TW)

(72) Inventor: **Hui Tsuo Chou**, Zhubei (TW)

(73) Assignee: **OptoMedia Technology Inc.**, Zhubei (TW)

(**) Term: **15 Years**

(21) Appl. No.: **29/808,892**

(22) Filed: **Sep. 23, 2021**

(51) **LOC (15) Cl.** **13-03**

(52) **U.S. Cl.**

USPC **D13/133**

(57) **CLAIM**

The ornamental design for a fiber optic connector, as shown and described.

DESCRIPTION

FIG. 1 is a perspective view of a fiber optic connector showing our new design according to an embodiment of this design;

FIG. 2 is a front view according to the embodiment of this design;

FIG. 3 is a rear view according to the embodiment of this design;

FIG. 4 is a right side view according to the embodiment of this design;

FIG. 5 is a left side view according to the embodiment of this design;

FIG. 6 is a top view according to the embodiment of this design; and,

FIG. 7 is a bottom view according to the embodiment of this design.

The broken lines illustrate portions of the fiber optic connector and form no part of the claimed design.

The dot-dash broken line portion of the figure drawings is included to show boundaries of portions that form no part of the claimed design.

1 Claim, 6 Drawing Sheets
